United States Patent Office.

HARVEY T. LEE, OF MARYSVILLE, CALIFORNIA.

Letters Patent No. 102,282, dated April 26, 1870.

METALLIC PACKING FOR STATIONARY JOINTS.

The Schedule referred to in these Letters Patent and making part of the same.

To all whom it may concern:

Be it known that I, HARVEY T. LEE, of Marysville, county of Yuba, State of California, have invented an Improved Metallic Packing for Stationary Joints; and I do hereby declare the following description and accompanying drawings are sufficient to enable any person skilled in the art or science to which it most nearly appertains to make and use my said invention or improvements, without further invention or experiment.

My invention relates to an improved metallic packing to be used solely for rendering stationary joints steam and water-tight; and it is an improvement on a patent which was granted to Hall and Lee for an invention of the same character on the 8th day of June, 1869, in which they claimed upsetting or thickening the opposite edges of plates of malleable metal, so as to form wedge-shaped edges, upon which the corners of the joint to be packed were placed.

My present invention consists in forming a metal packing for stationary joints out of any malleable wire or other thin strips, rods, or bars of such metal, and, by giving it a peculiar shape, make it answer the same purpose as that covered by the patent above mentioned, and that at a less cost in its manufacture and production.

In order to more fully illustrate and explain my invention, reference is had to the accompanying drawings forming a part of this specification, in which—

A represents a steam-chest or other surface, upon which a cover is to be fitted so as to give a steam or water-tight joint.

To render this and other similar joints steam or water-tight, I take a suitable-sized wire, rod, bar, or strip of copper or other malleable metal, and give to it an oval or other shape which will produce two thin sharp edges upon opposite sides.

The sharp-edged wire thus formed I bend to the desired shape to fit around and upon the outer edge of the surface to be packed, in a manner similar to the oval wire, marked B, uniting the two ends with solder or other brazing material.

A second encircling band is then formed of the same material, and in the same manner, to fit around the inner edge of the surface, as shown by the wire marked C.

In order to protect the bolts D and prevent the steam from escaping beside a loosely-fitting one, I form rings, E, of the same material, which are then placed in the proper position between the outer and inner bands C and D, for encircling the bolts and secure them to the bands C and D by brazing or soldering, as above described. These rings serve to unite the packing-frame, and thus prevent their becoming displaced.

After this packing-frame has been properly placed upon the surface of the steam-chest, the cover is placed down upon the frame, when, by turning the nuts firmly and strongly down upon the cover, the thin edges of the wires will be compressed, or rather upset, so as to fit closely to both surfaces, filling any depressions or unevenness in either of the parts, and thus furnishing a perfectly steam and water-tight joint.

A packing made in this manner can be fitted upon surfaces of various sizes, and, consequently, can be manufactured and put upon sale; whereas, all the usual and ordinary forms have to be manufactured expressly for and fitted to the particular surface upon which it is to be applied, unless two surfaces should be synonymous.

Having thus described my invention, What I claim, and desire to secure by Letters Patent, is—

A packing for stationary joints made out of malleable metallic strips, wires, or rods, by forming upon them two opposite sharp edges, substantially as above described.

In witness that the above-described invention is claimed by me, I have hereunto set my hand and seal.

HARVEY T. LEE. [L. s.]
